United States Patent Office.

EPHRAIM C. HODGE, OF ONEONTA, AND DELOS H. MANN, OF DELHI,
NEW YORK.

Letters Patent No. 91,538, dated June 22, 1869.

IMPROVEMENT IN CARRIAGE-SPRINGS.

The Schedule referred to in these Letters Patent and making part of the same.

To all whom it may concern:

Be it known that we, EPHRAIM C. HODGE, of the town of Oneonta, in the county of Otsego, and DELOS H. MANN, of the town of Delhi, in the county of Delaware, both in the State of New York, have invented certain new and useful Improvements in Wooden Springs for Wheeled Vehicles; and we do hereby declare that the following is a full and exact description thereof, reference being had to the accompanying drawings, and to the letters of reference marked thereon, making a part of this specification, in which—

Figure 1 is a perspective view of our invention, as combined for use.

Figure 2 is a transverse section of the cross-piece F, which connects the springs C, and on which the springs D rest, said section showing the rolling-joint, and method of attaching the springs D to the cross-piece F.

Figure 3 shows another method of attaching the springs D to the cross-pieces F, the rolling, or hinge-joint being entirely of metal.

Like letters of reference indicate like parts.

The nature of our invention consists in combining a series of wooden springs with the running parts and body of a wheeled vehicle, in such a manner as to produce an easy motion of the body on the springs, while, at the same time, the whole combination will be light, durable, and cheap.

To enable others skilled in the art to make and use our invention, we will proceed to describe more fully its manner of construction and operation.

A represents two wooden reaches, running parallel with each other, and attached, at their extremities, to the axle, in rear, and head-block in front.

B represents two arched wooden-springs, (or elevating-arches,) resting upon, and attached, at their extremities, to the wooden reaches A, as shown in fig. 1.

C represents two wooden springs, running parallel with each other, and secured, at the middle, or centre, to the top of the arched springs, or elevating-

pieces B, by means of metal clips, or bolts, and connected, at their extremities, by two wooden cross-pieces, F, as shown in fig. 1.

D represents two wooden springs, placed between, and running parallel with the springs C, at a short distance from them.

The springs D are attached, at their extremities, to the cross-pieces F, by means of a rolling, or hinge-like joint, as shown in fig. 2, in which D is the spring, F, the cross-piece, and G, the clip, or portion of hinge-strap, connecting the whole together, in such a manner as to allow a rolling, or hinge-like motion, the use of which is to allow more freedom of motion to the springs C and D, so that they may act, to a certain extent, independent of each other, and not cramp, which they would naturally do, were the springs D also secured to the cross-pieces F, in such a manner as to have no motion thereon.

If desired, this rolling joint may be made entirely of metal, and secured to the cross-piece F and spring D, as shown in fig. 3.

The body of the vehicle may be attached to the springs D, by means of rubber or elliptic steel springs E, or by means of saddle-blocks, placed at the centre; but as such devices are commonly used for connecting the bodies of wheeled vehicles with the running-parts, we make no claim to such.

What we claim as our invention, and desire to secure by Letters Patent, is—

In combination with a wheeled vehicle, the reaches A, arched pieces B, springs C, cross-pieces F, and springs D, the whole being combined, arranged, and operating, in the manner and for the purposes set forth in the above specification.

EPHRAIM C. HODGE.
DELOS H. MANN.
